HINGE FOR TYPE CASTING MACHINES

George A. Field, Minneapolis, Minn.

Application June 29, 1933, Serial No. 678,176

3 Claims. (Cl. 16—179)

This invention relates to a stereotype casting machine, and particularly to a hinge structure for such a machine.

As is well known, such casting machines comprise a pair of rather large rectangular plates which have comparatively flat adjacent surfaces brought into close parallel relation when the plates are inclosed or casting position. One plate, usually the upper plate, is adapted to swing away from the other plate so that said plates extend at a wide angle when in open or discharging position.

It is an object of this invention to provide a simple, inexpensive and efficient construction of hinge for such a pair of plates.

It is a further object of the invention to provide a hinge for such a pair of plates constructed and arranged to hingedly connect said plates and insure that the plates will swing to open position smoothly and be held in proper open position.

It is more specifically an object of the invention to provide a hinge for such a pair of plates, comprising lugs of novel construction projecting from adjacent ends of said plates connected by pintle means and cooperating with suitable stop means.

These and other objects and advantages of the invention will be fully set forth in the following description made in connection with the accompanying drawing, in which like reference characters refer to similar parts throughout the several views and in which:—

Fig. 1 is a vertical section taken on line 1—1 of Fig. 2 as indicated by the arrows;

Fig. 2 is a top plan view as seen from line 2—2 of Fig. 1 as indicated by the arrows;

Fig. 3 is a view similar to Fig. 1 showing the plates in open position;

Fig. 4 is a vertical section taken on line 4—4 of Fig. 6 as indicated by the arrows, showing a modified construction;

Fig. 5 is a view of the plates shown in Fig. 4, swung to open position, an intermediate position being indicated in dotted lines; and

Fig. 6 is a plan view as seen from line 6—6 in Fig. 4 as indicated by the arrows.

Referring to the drawing, particularly Figs. 1 to 3, one plate 10 is shown as the upper plate of a stereotype casting machine as illustrated, which is superimposed on or engages the other plate 11. These plates are customarily of rectangular form and only one lower corner is shown in Fig. 2. A lug 12 projects from the end of plate 10, said lug having its top surface substantially flush with the top surface of plate 10 and curving downwardly somewhat on its top at its outer end. The lower surface of lug 12 has a flat or plane portion 12a at its outer end and said under side is curved at 12b and connected to the inner or bottom surface of plate 10 by a small fillet. Plate 11 has a projection or lug 13 at one end which is below or

aligned with lug 12 longitudinally of said plates. Lug 13 has a flat outer surface 13a adapted to form a stop surface and to be engaged by surface 12a when plate 10 is in open position as shown in Fig. 3. As shown in Figs. 1 and 3, lug 13 has a top surface 13b extending substantially at a right angle to surface 13a and forming a corner with said surface. The surface 13b and said corner are adapted to be engaged by the under side of lug 12 as plate 10 swings to open position. Another lug 14 is provided, carried by and projecting from one end of plate 11. Lug 14 is disposed at one side of lug 12 and closely adjacent thereto. As shown in Fig. 1, lug 14 extends substantially to the top of lug 12, the same having a semi-cylindrical top and said lug has extending therethrough an elongated slot 14a. A pintle rod 15 is provided which extends through slot 14a and also through an aperture formed in lug 12, which substantially fits said rod. A washer 16 encircles rod 15 adjacent the inner side of lug 14 and is held in such position by a split key 17a extending through rod 15. It will be understood that there is one of the lugs 12, 13 and 14 at each side of the plates so that the parts shown in Fig. 2, which shows the lower left hand corner of the plates, are duplicated at the lower right hand corner of the plates.

In operation, when the plates are in closed or casting position, the parts occupy the positions shown in Figs. 1 and 2. When it is desired to open the plates, plate 10 is swung about the axis of the pintle 15 and surface 12b rides on surface 13b or the corner formed thereby and rod 15 moves in slot 14a. The swinging movement of plate 10 continues until surface 12a engages the surface 13a as shown in Fig. 3 and plate 10 is thus held in this position by gravity.

Referring to Figs. 4, 5 and 6, plates 10 and 11 are shown and plate 10 has projecting therefrom, adjacent one corner thereof, a lug 17. Lug 17 has its top surface substantially flush with the top of plate 10 and curves downwardly somewhat at its top adjacent its outer end. A lower surface of lug 17 is substantially flat and substantially flush with the lower surface of plate 10. Lug 18 projects from plate 11 beneath lug 17, or aligned with lug 17 longitudinally of the plates. Lug 18 has its bottom surface substantially flush with the surface of plate 11, said bottom surface of said lug curving upwardly towards its outer end. The top surface 18a of lug 18 is disposed somewhat below the top or inner surface of plate 11, the end of said plate adjacent said lug thus forming a shoulder constituting a stop surface 11a. Said top surface 18a curves upwardly toward its outer end terminating some distance inwardly of the end of lug 18, said lug thus having a flat top portion lying closely adjacent and parallel to the flat under portion of lug 17 when the plates are in closed position. The distance 60

between these two portions of lugs 17 and 18 will be determined by the thickness of the plate being cast between members 10 and 11.

A lug 19 is provided carried by and projecting from the end of plate 11, said lug being disposed closely adjacent one side of lug 17 and as shown in Fig. 6, at the outer side thereof. Lug 19 has substantially vertical inner and outer sides and has a semi-cylindrical top. Lug 19 has an elongated slot 19a therein and as shown in Fig. 4, said lug projects somewhat above the top of lug 17 when the plates are in closed position. A pintle rod 20 is provided, the same extending through slot 19a and through an aperture substantially fitting the same in lug 17. Rod 20 is threaded at its outer end to receive a nut 21, which engages the outer side of lug 19.

The parts 17 to 21 are reproduced at the other side of the plates. Fig. 6 shows the lower left hand corner of the plates and there will thus be lugs 17, 18 and 19 at the lower right hand corner of the plates and rod 20 will extend through the lugs 17 and 19 at the right hand corner of the plates and have another nut 21 threaded thereon engaging the outer side of the other lug 19.

In operation, when the plates are in closed position, the parts occupy positions as shown in Fig. 4. When the plates are to be moved to open position, plate 10 is swung about the axis of pintle 20. The end of lug 17 swings inwardly and rides on the surface 18a. Pintle 20 moves vertically in slot 19a and plate 10 moves to fully open position with the lower flat side of lug 17 engaging the stop surface 11a and said plate is held in this position by gravity. In the modification shown in Figs. 1 to 3, plate 10 is swung back to closed position with surface 12b engaging the surface 13b and corner of lug 13, pintle rod 15 moving in slot 14a. In the form shown in Figs. 4, 5 and 6, the plate 10 swings back to closed position with the end of lug 17 closely adjacent the end of lug 18 and rod 20 moving in slot 19a.

The slots 14a and 19a are provided to accommodate movement of pins 15 and 20 respectively. The stereotype plates cast between plates 10 and 11 are of different thicknesses and filling strips of different thicknesses are used between plates 10 and 11. The pins 15 and 20 can take different positions in slots 14a and 19a respectively in accordance with the plates being cast.

From the above description it is seen that applicant has provided a simple and efficient structure of hinge for the plates on a stereotype casting machine. The structure is easily and inexpensively made in connection with the plates and the swinging movement of the movable plate is controlled so that it swings easily and smoothly to open position. The swinging plate thus swings to open position without jar or shock and is held in open position by gravity. The novel structure has been amply demonstrated in actual practice and has been found to be successful and efficient and the same is being commercially made.

It will, of course, be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:—

1. A hinge for the plates of a stereotype casting machine comprising a lug projecting from one end of one plate longitudinally thereof and disposed substantially between the planes of the top and bottom surfaces of said plate, said lug having a curved surface on its side adjacent said other plate, said surface terminating in a substantially flat surface adjacent the end of said lug, said other plate having a projection at its end with a surface inclined at an obtuse angle to the top 10 of said plate and having a corner formed by said surface and another surface adjacent the top of said plate, said other plate also having a lug projecting from said end having a portion extending transversely of said first mentioned lug, said 15 portion having an elongated slot therein extending substantially at right angles to the top surface of said other plate and a rod extending in and substantially rigid with said first mentioned lug and passing through said slot, said curved surface of said first mentioned lug sliding over said corner on said other plate as said plates are swung to open position and said substantially flat surface on said first mentioned lug engaging said inclined surface on said other plate when the plates 25 are in open position.

2. A hinge structure for the plates of a stereotype casting machine, which plates have substantially flat surfaces and are arranged to be positioned with said surfaces parallel and in close 30 proximity comprising a lug projecting from one plate and having an elongated slot therein, a pintle extending through said slot, a lug projecting from the other plate and disposed at one side of said lug, said pintle extending into said last mentioned lug and substantially fitting therein, said last mentioned lug having a stop surface beyond said pintle, said latter plate being swingable and a third lug projecting from said first mentioned plate having a stop surface and an edge at one 40 end of said surface, said third lug being aligned with said second mentioned lug and said edge being engaged by said second mentioned lug as said last mentioned plate swings to open position, said stop surfaces being in contact when 45 said plates are in open position.

3. A hinge structure for the plates of a stereotype casting machine, which plates have substantially flat surfaces and are arranged to be positioned with said surfaces parallel and in close 50 proximity, one of said plates being movable and the other stationary, having in combination, a stop means on said stationary plate, a lug projecting from one end of said stationary plate and having an elongated slot therein having its longitudinal axis extending substantially perpendicular to the substantially flat surface of said plate, a pintle extending through and movable in said slot, a lug projecting from the end of said movable plate at one side of said lug in which said pintle is received and substantially fits, said latter lug having a stop surface at the side of said pintle remote from said plate, said movable plate swinging about the axis of said pintle, said stationary plate also having a portion engageable by said last mentioned lug as said movable plate swings to open position adapted to partially bear the weight of said movable plate, said stop surface on said second mentioned lug moving into engagement with said stop means to hold said 60 plates in open position.
